DESIGN FOR A CASING FOR BOILER BURNER UNITS OR THE LIKE

Henry J. Sandlas, Jr., Randallstown, Md., assign-
or to May Oil Burner Corporation, a corpora-
tion of Maryland

Application June 8, 1939, Serial No. 85,401

Term of patent 7 years

To all whom it may concern:

Be it known that I, Henry J. Sandlas, Jr., a citizen of the United States and residing at Randallstown, county of Baltimore, State of Maryland, have invented a new, original, and ornamental Design for Casing for Boiler Burner Units or the like, of which the following is a specification, reference being had to the accompanying drawing, forming part thereof.

Figure 1 is a perspective view showing the front,

top and one side of my new design for a casing for a boiler burner unit or the like.

Figure 2 is a rear elevational view of the casing shown in Figure 1.

Figure 3 is an elevational view of the other side of the casing shown in Figure 1.

I claim:

The ornamental design for a casing for boiler burner units or the like, substantially as shown.

HENRY J. SANDLAS, Jr.
